UNITED STATES PATENT OFFICE.

JONATHAN M. CHENEY, OF ASHLAND, NEW HAMPSHIRE.

THROTTLE CONTROL FOR MOTOR-VEHICLES.

1,115,395.

Specification of Letters Patent. Patented Oct. 27, 1914.

Application filed December 4, 1913. Serial No. 804,681.

To all whom it may concern:

Be it known that I, JONATHAN M. CHENEY, a citizen of the United States, and a resident of Ashland, in the county of Grafton and State of New Hampshire, have invented certain new and useful Improvements in Throttle Control for Motor-Vehicles, of which the following is a specification.

This invention relates to the means for controlling the throttle valve of the carburetor of internal combustion engines for motor vehicles, the invention relating especially to improved means whereby the throttle may be controlled either by the hand or foot of the user.

The object of the invention especially is to provide means adapted to the Ford cars in which the steering post is at the left of the car while the carburetor and its throttle are located at or near the right.

The invention consists in the improvements which I will now proceed to describe and claim.

Of the accompanying drawings:—Figure 1 is a plan view of so much of a Ford car having my improvements attached thereto, as is necessary for an understanding of the mechanism. Fig. 2 represents a section on line 2—2 of Fig. 1. Fig. 3 is a detail view of the parts carried by the foot-board of the car, looking from the line 3—3 of Fig. 2, and omitting the body and foot-board of the car. Fig. 4 is a view similar to a portion of Fig. 2, on a larger scale. Fig. 5 is a perspective detail illustrating the lost motion connection hereinafter described.

A portion of the body of the car is illustrated at 10, the usual foot-board being indicated at 11. The post 12, steering wheel 13, steering spindle 14, and the throttle spindle 15 are illustrative of the type employed in the Ford cars. The spindle 15 has an arm 16 secured to it, and a sleeve 17 having a swivel connection with said arm as best illustrated in Fig. 5. Slidably mounted in the sleeve 17 is a rod 18 having an end which projects through the sleeve provided with a suitable stop which is illustrated as consisting of a bent end 19. The other end of the rod 18 is connected to an arm formed on a yoke piece 20 which is secured to the stem 21 of the carburetor throttle valve. When the hand lever 35 of the spindle 15 is operated in the usual direction to actuate the carburetor throttle, the sleeve 17 is

moved so that it acts upon the stop 19 to pull the rod 18 in the direction indicated by the arrow in Fig. 5, while the lost motion connection provided by means of the rod 18, 60 stop 19, and sleeve 17, will permit the rod 18 to be shifted in the direction of the arrow in Fig. 5 without any resistance being caused by the usual hand control devices. Provision for lost motion is necessary at some part 65 of the mechanism, in order to permit the foot control mechanism to be operated without resistance by the hand control devices. The sleeve 17 and the rod 18 constitute a two-part connection between the spindle arm 16, 70 and the valve stem arm or yoke piece, the part 18 of said connection being movable in one direction independently of the other part 17, and the two parts being provided with complementary abutments which cause 75 their movement in unison in the opposite direction. One of said abutments is the bent end 19, and the other is the end of the sleeve 17 which bears on said bent end. It is obvious that a two-part connection, one 80 part of which is movable independently in one direction, the two parts being caused to move in unison in the opposite direction, may be made in different ways.

I will now describe the foot control devices which include a plate 22 secured to the foot-board 11 as by suitable screws, said plate having a grooved portion 23 providing a bearing for a rock shaft 24 having a pedal 25 at one end and an arm 26 at the other end, 90 said arm projecting downwardly through a small slot 29 in the foot-board. The bearing plate 22 and the rock shaft are of such length as to provide for the pedal being located in convenient proximity for the person operating the car, and sitting behind the hand wheel 13, while the connections with the other end of the shaft 24 are at the right to correspond with the location of the carburetor and its throttle. 95

The bearing plate 22 enables the rock shaft to be operatively mounted in position without requiring any alteration of the foot-board other than making the small slot 29. In order that the rock shaft may be kept 100 properly lubricated, the plate 22 may have one or more oiling holes 27 as indicated in Fig. 1.

The arm 26 is connected by means of a rod 28 with the yoke piece 20, which in this 110 embodiment of the invention has two arms, one engaged with the rod 18, and the other

with the rod 28, and the parts are held yieldingly in the initial positions illustrated in Figs. 1 and 2 by means of a suitable spring 30 connected at one end to the pivotal connection of the arm 26 with rod 28, and at the other end with an arm 31 of a bracket secured to the under face of the foot-board 11, said bracket having a lug 32 projecting behind the arm 26 to serve as a limiting stop 19 to hold the parts in their initial positions.

It will now be understood that the person operating the machine, and having one foot upon the pedal 25, may actuate the rock shaft so as to cause the connecting rod 28 15 to shift the throttle valve stem in the same direction as that which is imparted to it when the hand throttle spindle 15 is operated, actuation by means of the pedal 25 simply causing the rod 18 to shift in the direction of the arrow in Fig. 5 without transmitting any motion to the arm 16 and spindle 15.

It will now be seen that the hand-controlled spindle 15, the foot-controlled rock-shaft 24, and the rods 18 and 28, directly connecting the arms of said spindle and rock-shaft with the throttle-valve stem, constitute a very simple and effective hand and foot-controlled throttle-valve operating 25 mechanism which may be easily applied to a Ford car without modification or alteration of the car, other than making the slot 29 in the foot-board, attaching the yoke piece 20 to the valve-stem, and applying the sleeve 17 to the rod 18. The rod 18 and spindle-arm 16, as here shown, are the same as those now used in the Ford car to connect the spindle 15 with an arm on the valve-stem, the bent end 19 of said rod being adapted to enter 30 the orifice in the arm 16; hence, the only change from the Ford construction required at this point, is the removal of the bent end 19 from the arm 16, and the application of the sleeve 17 to the rod 18, said sleeve having 35 a swivel connection with the arm 16, as above stated. The parts of said mechanism and the throttle valve are adapted to be yieldingly held in their initial positions by a single spring 30 which simultaneously 40 turns the valve, the spindle, and the rock-shaft, to their starting positions, and yieldingly presses one of the above-mentioned abutments against the other when pressure is removed from the hand lever 35, or the 45 pedal 25.

It is to be understood that I do not limit myself to the exact details of construction illustrated and described, but intend to include within my invention all such modifications or mechanical equivalents as fall within the terms of the appended claims.

I claim:

1. In a motor vehicle the combination of the engine throttle-valve having a yoke piece 60 on its stem, a hand-controlled spindle having

a hand-lever and an arm, a foot-controlled rock-shaft having a pedal and an arm, and two rods, one connected with the spindle and the other with the rock-shaft arm, and both having direct connections with the valve-stem yoke piece, one of said rods having a lost motion engagement with the spindle arm, providing for a movement of the rod in one direction without corresponding movement of or resistance by the spindle. 70

2. In a motor vehicle the combination of the engine throttle-valve having a two-armed yoke piece on its stem, a hand-controlled spindle having a hand lever and an arm, a foot-controlled rock-shaft having a 75 pedal and an arm, a pull-rod having a lost motion engagement with the spindle arm, providing for a movement of the rod in one direction without corresponding movement of or resistance by the spindle, said pull-rod being connected with one of the yoke-piece 80 arms, and a push-rod connected with the rock-shaft arm and with the other yoke-piece arm. 85

3. In a motor vehicle the combination of the engine throttle-valve, a hand-controlled spindle having a hand lever and an arm, a foot-controlled rock-shaft having a 90 pedal and an arm, two rods, one connected with the spindle arm, and the other with the rock-shaft arm, and both having direct connections with the throttle-valve stem to transmit motion thereto, one of said rods having a lost motion engagement with the spindle arm, providing for a movement of the rod in one direction without corresponding movement of or resistance by the spindle, and a 95 spring which yieldingly holds the spindle, the rock-shaft, the rods, and the valve-stem, in their initial positions. 100

4. In a motor vehicle the combination of the engine throttle-valve having an arm on its stem, the hand-controlled spindle also having an arm, a two-part connection between the arms of the spindle and valve-stem, a rock-shaft having a pedal and an arm, and a rod connecting the rock-shaft arm with the valve-stem arm, one of the parts of the said two-part connection being movable in one direction independently of the other, and the said parts being provided with complementary abutments which cause their movement in unison in the opposite direction. 110

5. In a motor vehicle the combination of the engine throttle-valve having an arm on its stem, the hand-controlled spindle also having an arm, a two-part connection between the arms of the spindle and valve-stem, the parts of said connection having 115 complementary abutments, causing them to move in unison in one direction, and one of said parts being independently movable in the opposite direction, a rock-shaft having a 120 pedal and an arm, a rod connecting the rock- 125

shaft with the valve-stem arm, and a spring which yieldingly holds the spindle, the rock-shaft, and the valve-stem in their initial positions, said spring normally holding the 5 said abutments in yielding contact with each other.

6. In a motor vehicle, the combination with the engine throttle valve, of a rotatably mounted spindle having an arm, a sleeve 10 having a swivel connection with said arm, a rod mounted in said sleeve and having a stop at one end of the sleeve, the other end of said

rod being connected to the throttle valve to actuate the latter in one direction, and a pedal and connections between it and the engine throttle valve to actuate the latter in the same direction as that imparted to it by the rod mounted in said sleeve. 15

In testimony whereof I have affixed my signature, in presence of two witnesses.
